UNITED STATES PATENT OFFICE.

JOHN NICOLET, OF CANTON, OHIO.

SHOE-BLACKING MACHINE.

SPECIFICATION forming part of Letters Patent No. 706,091, dated August 5, 1902.

Application filed March 29, 1902. Serial No. 100,575. (No model.)

To all whom it may concern:

Be it known that I, JOHN NICOLET, a citizen of the United States, residing at Canton, in the county of Stark and State of Ohio, have 5 invented a new and useful Shoe-Blackening Machine, of which the following is a specification.

This invention is an improved boot and shoe polishing machine, and has for its object to provide a machine for mechanically cleaning and polishing boots and shoes, and thereby relieving the attendant of the arduous task of performing such labor by hand.

With the above objects in view my invention comprises a stand having a foot-rest positioned thereon upon either side of which is mounted a reciprocating brush for cleaning the sides of the shoe, and in advance of the said brushes is mounted a revolving brush for cleaning the top of a shoe; and a further object of my invention is to provide one of the said reciprocating brushes with a lateral movement, whereby the said brush may be adjusted to or from the foot-rest for the purpose of accommodating shoes of various widths.

With these briefly-stated objects in view my invention consists also in certain details of construction and novelties of combination and arrangement, as will be fully described 30 in the following specification and pointed out in the claims, reference being had to the drawings, in which—

Figure 1 is a perspective view of my improved boot or shoe polishing machine. Fig. 35 2 is a cross-section of the same, the said section being taken in advance of the reciprocating brush. Fig. 3 is a transverse section taken about on the line 3 3 of Fig. 2. Fig. 4 is a detail view of the foot-rest. Fig. 5 is a 40 detail view of one of the brushes, and Fig. 6 is a detail view of the crank-shaft.

In carrying out my invention I employ a stand A, which may be of any desired height, and on one side of which is positioned a step, 45 by which a person may ascend and take position upon the stand. The said stand may be ornamented in any suitable manner, the drawings illustrating the front having a shield A', and around the sides and rear of the stand 50 is positioned a suitable rail A².

The top of the stand is provided with two

slots A³, in which are designed to operate blocks B, which are supported and slide upon suitable brackets B', that are fixedly held to the under side of the platform, as clearly indicated in Fig. 2 of the drawings. The said blocks B project up through the slots and have their upper faces provided with grooves b, in which are held the lower ends of brush-carrying arms C, having suitable brushes D 60 connected thereto and which are arranged on opposite sides of a foot-rest E, which is pivotally mounted upon a bracket E', the base of which is slidably held in grooves formed in guide-strips E³, which are arranged upon the 65 upper side of the platform of the stand and adjacent the inner edges of the slots A³. One of the said brush-carrying arms C is provided with a slot C', through which extends the horizontal member of a crank-arm F, which 70 is pivotally positioned upon the said platform and has one end terminating in an upwardly-bent handle-lever F', carrying a spring-actuated pawl that engages the rack F² and by which the said crank-arm is pivotally held in 75 any position to which it is adjusted. By this arrangement it will be readily understood that the brush-carrying arm may be readily and quickly moved to or from the foot-rest E 80 to accommodate various-sized shoes.

The blocks B, upon which the brushes are mounted, are operated by pitmen B², which are connected at their opposite ends to crank portions B³, formed in the shaft B⁴, which has one end projecting through the side of 85 the stand and provided with a fast and loose pulley B⁵ and B⁶, respectively. The belt-pulley B⁷ is also mounted upon the shaft within the stand and has a belt G operating thereon, which also runs over a pulley H, 90 carried upon a shaft H', which is supported within the stand by means of bracket-arms H². Upon the shaft H' is also mounted a pulley similar to the pulley H, over which runs a belt I, that also engages a belt-pulley I', 95 mounted upon a brush-carrying shaft J, which is held in brackets J' upon the forward end of the stand and in advance of the reciprocating brushes. The shaft J is provided with a brush J³, which is arranged directly in 100 front of the foot-rest, and over the said brush is a shield or guard K, that is fastened to

the front portion A' of the stand. A suitable chair or seat L is arranged upon the stand, as shown.

In operation a person is seated upon the 5 chair and places one foot upon the foot-rest E, and the laterally-movable block C is then moved to the proper distance by means of the lever F', when the operating-belt (not shown) is transferred from the loose to the 10 fast pulley, which revolves the shaft and through the medium of the pitmen reciprocates the brushes, which quickly and effectively cleans and polishes the side of a shoe. While the sides of the shoe are thus being 15 cleaned the person pushes upon the foot-rest until his shoe engages the revolving brush J³, when the top of the shoe is quickly and effectively cleaned and polished.

It will of course be understood that the 20 brush J is operated through the medium of the pulleys and belts, as hereinbefore described. It will thus be seen that I provide an exceedingly effective machine by which one's shoes may be quickly and easily cleaned 25 and polished, and it will of course be understood that the attendant in charge of the stand is provided with suitable polishing materials, that are placed upon the shoe before being operated upon by the brushes.

30 Having thus fully described my invention, what I claim as new, and desire to secure by Letters Patent of the United States, is—

1. In a shoe-polishing machine the combination of a stand, a bracket slidably mounted thereon, a foot-rest pivotally held to the bracket, reciprocating blocks positioned upon the frame and having brushes removably connected thereto, one of the said brushes being movable to and from the said foot-rest, a revolving brush mounted upon the stand in advance of the said foot-rest, and means for operating the said brushes, substantially as set forth.

2. In a shoe-polishing machine, the combination with the stand, having slots arranged in the upper surface thereof, brackets secured to the stand below the said slots, brush-carrying blocks slidably retained upon the said brackets, a crank-shaft mounted within the 45 stand, pitmen connecting the said cranks of the shaft with the said blocks, a brush-carrying shaft revolvably mounted upon the upper portion of the forward end of the stand, a foot-rest slidably held between the said 50 stand, sliding brushes, and means for adjusting one of the said sliding brushes to or from the foot-rest, and means for operating the said brushes, substantially as shown and described.

60 3. In a shoe-polishing machine, the combination of a stand having slots formed in the

upper surface thereof, brackets positioned upon the under side of the said upper surface and below the said slots, blocks slidably retained upon the said brackets, brush-carrying arms mounted upon the said blocks, brushes held upon the arms, one of said arms having a slot formed therein, a crank-shaft projecting through the said slot and having one end terminating in a handle-lever, the 65 said shaft being mounted upon the stand at the ends of one of the said slots, a shaft mounted upon the stand and at the forward end thereof, a brush positioned upon the shaft, and means for operating the said sliding brushes, and means for operating the said revolving brush, substantially as shown and described.

4. In a shoe-polishing machine, the combination of a stand, having slots formed in the 80 upper surface thereof and brackets held upon the under side of the stand and directly below the said slots, blocks slidably held upon the brackets, brush-carrying arms positioned upon the said blocks and having brushes arranged at their upper ends, guide-strips arranged upon the platform upon either side of the slots, a bracket slidably retained in the said strips, a foot-rest pivotally mounted upon the bracket, a shaft carrying a brush 85 mounted upon the platform in advance of the said foot-rest, and means for operating said brushes, substantially as shown and described.

5. In a shoe-polishing machine, the combination of a stand having an adjustable foot-rest mounted thereon, brushes slidably positioned upon either side of the foot-rest, one of which is movable to and from the said foot-rest, a brush revolvably mounted upon the 90 stand at the forward end of the foot-rest, means for operating the said brushes, and means for operating said movable brush to or from the said foot-rest, substantially as shown and described. 95

6. In a shoe-polishing machine, the combination of a frame, reciprocating blocks arranged thereon, brushes carried by the blocks, one of which is movable laterally, a bracket slidably arranged upon the stand between the said brushes, a foot-rest pivotally connected to the bracket, a shaft mounted upon the frame in advance of the said brushes and foot-rest, and having a brush mounted thereon, a guard arranged over the revolving 100 brush, and means for operating the brushes substantially as shown and described. 110
